UNITED STATES PATENT OFFICE

JOHN A. AMOS, OF CHICAGO, ILLINOIS, ASSIGNOR TO THE PYLE-NATIONAL COMPANY, OF CHICAGO, ILLINOIS, A CORPORATION OF NEW JERSEY

ELECTRIC SWITCH

Application filed December 17, 1926. Serial No. 155,370.

My invention relates to improvements in electric switches particularly for use in connection with locomotive electric systems and has for one object to provide a new and improved form of electric switch wherein the switch member may be easily moved by the operator from the on to the off position and vice versa and wherein the switch mechanism will positively remain in the position in which it was placed by the operator. Another object is to provide a switch arrangement which will be fool proof and durable so as to stand up under the very difficult problems of railroad service. Other objects will appear from time to time throughout the specification and claims.

My invention is illustrated more or less diagrammatically in the accompanying drawings, wherein—

20 Figure 1 is a plan view in part section with cover removed of a switch and housing;

Figure 2 is a section along the line 2—2 of Figure 1;

25 Figure 3 is a perspective of the switch plunger.

Like parts are indicated by like characters throughout the specification and drawings.

A is the switch housing which in this case takes the form of a box or retainer casting 30 having flanges A¹ about which the housing may be mounted in place. A cover A² outwardly flanged at A³ inwardly flanged at A⁴ and provided with a dust tight packing strip A⁵, screws A⁶ may be used to fasten the cover in place to close the box. On either side of the box are hollow lugs A⁷, in this case associated with the lugs A¹ onto which conduits may be screwed to contain the conductor A⁸. On another side of the box is 40 a hollow boss A⁹ serving as a guide for the switch handle.

B is an insulating block contained within the housing. Upon this insulating block are mounted binding posts B¹ to which lead 45 the conductors A⁸. Associated with these binding posts are inwardly extending spring fingers B² which never come in contact one with the other. B³ is a sliding insulating block, adapted to travel on the block B. 50 This block carries a conducting jacket B⁴ so

arranged that when the parts are in the position shown in full lines in Figure 1, the conducting jacket is out of contact, when in the position shown in dotted lines the contacting jacket engages both fingers and closes 55 a circuit between them. It will be noted that this block is tapered as at B⁵ to insure easy engagement with the spring fingers.

This sliding block B³ is guided in the fixed insulating block B and is held therein by 60 means of a spring plate B⁶ which spring plate terminates in a lock finger B⁷ adapted to engage an enlargement B⁸ on the block B³.

C is the switch handle comprising a cylindrical portion adapted to travel in and be 65 guided by the sleeve A⁹, a hand button C¹ and a squared shank C² from which shank projects a switch controlling rod C³, which rod is slidable in the block B³. The block B³ is recessed around this rod and a coil 70 spring C⁴ is interposed between the bottom of one of the recesses and the member C² and a spring C⁵ between the bottom of the other recess and a head C⁶ so that the connection between the hand piece and the sliding block 75 is a spring connection and not a positive connection, the result being that there is certain freedom of movement with respect to the sliding block and a push or pull on the hand piece while it is sufficient to shift the block 80 into or out of position.

I claim:

1. A switch comprising an insulating supporting block, a rectangular insulating block adapted to slide on the supporting block, having its longer axis parallel with its direction of sliding, recesses in line with the major axis of the block terminating short of the center of the block and a relatively small aperture joining such recesses, a pin extending through the recesses and apertures, springs one in each recess, surrounding the pin, each abutting at one end in the bottom of the recess, and at the other end, on the pin, a handle whereby the pin may be longitudinally moved, the ends of the block removed from the handle being forwardly tapered, a conducting jacket encircling the block and terminating short of the ends thereof, the jacket being upwardly bulged on one 100

side of the block only, two opposed leaf conducting springs extending into the path of the block, adapted to be wedged apart thereby and adapted when the block is in one position to engage the conducting jacket and when the block is in the opposed position, to be out of contact therewith, a holding spring adapted to engage the bulge on the jacket to hold the block in a retracted position and an insulating support for said spring.

2. A switch comprising an insulating supporting block, a switch block slideable thereon, a thin conducting jacket encircling the switch block and upwardly bulged on one side thereof, means for moving the block longitudinally, an insulated holding spring adapted to engage the bulge on the jacket, two opposed conductor springs adapted when the block is in one position to both engage the jacket on opposed sides of the block, and adapted when the block is in the retracted position to be out of contact with the jacket.

Signed at Chicago, county of Cook and State of Illinois, this 10th day of December, 1926.

JOHN A. AMOS.
